CONTINUOUS DIFFUSION BATTERY

Harold F. Silver, Denver, Colo.

Application April 20, 1949, Serial No. 88,648

3 Claims. (Cl. 127—6)

1

This application is a continuation-in-part of my co-pending application Serial Number 619,163, filed September 28, 1945, now Patent No. 2,468,720, for Continuous Diffusion Battery and Treatment, and the invention relates to a method of and apparatus for the treatment of divided solids material with liquid, and more particularly to a continuous diffusion method and apparatus useful in the processing of sugar beets, sugar cane, corn, other grain products, and the like.

Among the objects of the present invention are to provide a method and apparatus useful in carrying out the process of my above said co-pending application Serial Number 619,163, and particularly with an apparatus which does not require the use of an endless or continuous conveyer to circulate the divided material; to provide such apparatus in which an adequate hydraulic head is maintained by a circulating agitating impeller; and to provide diffusion apparatus which is adaptable not only to the treatment of sugar beets or cossettes produced therefrom, but also to the treatment of other materials, including sugar cane, grain such as corn, and other solids in divided or finely divided form, where in a solid and liquid contact treatment is to be carried out and the loose granular material is of such a character that when suspended in liquid it cannot be effectively carried along in a circuit with an endless conveyer.

Thus, a paramount object of the invention is to provide a battery of cells in series wherein, both the solids and liquid are continually kept flowing through the series of cells without any stagnation of fluid at any place or places, by rotary impeller means for maintaining the intermixture of solids and liquid in an almost constant state of agitation, to extract the maximum juices or other constituents of the solids with minimum power factor.

Other objects and advantages of the invention will become apparent from the following description, taken with reference to the accompanying drawing in which:

Fig. 1 is a side elevation, partly in section, of the apparatus constituting one embodiment of the invention;

Fig. 2 is a top plan view of the same; and

Fig. 3 is an enlarged cross section of the drainage device forming a part of the apparatus shown in Figs. 1 and 2.

For the handling of more finely divided material than sugar beet cossettes, such as corn or other cereal grains, treated for extraction of certain constituents therefrom, and particularly ma-

terial which cannot be effectively moved progressively by an endless or continuous conveyer of the type illustrated in my co-pending application above identified, the method and apparatus disclosed herein may be utilized. In such method, the liquid is moved generally counter-currently to the divided solids, and in each stage the liquids and solids are intermixed and move in the same direction, as in the method disclosed in said co-pending application, but the divided material is moved through the stages and kept in a state of agitation by an impelling force applied adjacent the lower end of the downward course and throughout the upward course of each stage, such impelling or agitating force thereby being applied to the intermixture of divided solids and liquid.

One form of apparatus adapted to carry out the above method comprises the embodiment of the invention disclosed herein. In such embodiment, there is no conveyer, and the cells, such as cells C1', C2' and C3' of Figs. 1 and 2, are preferably disposed side by side, in a single row, each cell consisting of a downward course provided by a housing 125 and an upward course provided by a larger compartment formed by a cylindrical tank 126. Divided material to be treated enters the upper end of the housing of the first cell C1', as through an inlet 127, while the liquid enters the cell through a pipe 128. The housing 125 of each cell may have a cross sectional shape at the top substantially that of an elongated rectangle, and at the bottom that of a circle, with sides which taper outwardly and ends which taper inwardly to connect the two.

The lower end of the housing 125 corresponds in cross section to the periphery of a centrifugal impeller 130, which is mounted in a housing 131 and is adapted to discharge the mixture of liquids and solids through an outlet 132 to the lower end of tank 126. Impeller 130 may be rotated by a shaft 133 which extends downwardly through the housing, and at its upper end is provided with a pulley 134, for which may be substituted any other suitable means for rotating the same.

The lower end of tank 126 is conical in shape to connect with pipe 132, the tank providing sufficient space for sufficiently slow upward movement of the mixture of liquids and solids to the upper end thereof to permit adequate extraction of the constituent to be removed. During such movement, the mixture is preferably slowly stirred or agitated in any suitable manner, such as by paddles 135 to maintain the solids thoroughly dispersed in the liquid and to avoid any

accumulation of solids or pockets of liquid at any particular point which might tend to block or retard the flow of the mixture therethrough or produce non-uniformity in the flow. Paddles 135 are mounted upon a vertical shaft 136 which extends through the top 137 of tank 126, and bearing structures 138 are provided inside of the tank for the shaft. The upper end of the shaft, above the tank, is provided with a pulley 139, or any other suitable drive means, for rotating the shaft relatively slowly.

The liquid and solids move through housing 125 faster than through the tank, due to the difference in cross-sectional area. Thus, the mixture moves slowly upwardly through the tank to a discharge level 141 above that of the liquid inlet level 142, and the liquid is removed from the solids by a cylindrical screen device S'', preferably rotated in the direction of the arrow of Fig. 1, so that as the liquid is drained from the solids, the solids will be carried over the top of the screen and slide onto an apron 143, which forms an inlet for the downward course of the next cell C2'.

The liquid flows by gravity from cell to cell, and the column of material in housing 125 maintains a hydraulic head upon impeller 130 to insure effective operation of the impeller, which not only mixes the solids and liquid, but also produces a velocity head which is converted into a static head to maintain the discharge liquid level in the tank above the inlet liquid level in the housing.

As will be evident, the liquid flowing through pipe 128 to the first cell, flows by gravity from outlet 144 of the previous cell in the liquid circuit, and the liquid similarly flows to each cell from the next previous cell of the liquid circuit, the first cell in the solids circuit being, of course, the last cell in the liquid circuit. The liquid discharged from cell C1' may be carried by suitable piping from outlets 144 thereof to the next processing step.

Screen device S'' may be constructed in substantially the same manner as the screen device 3 of the aforesaid co-pending application, and as indicated in Fig. 3, is provided with a plurality of slotted rings 70'. Such a screen device may also be provided with suitable cleaning means 145, similar to the one shown in said co-pending application.

If desired, the screen device may comprise a screen of perforated plate or woven wire mesh attached to a supporting framework, the more finely divided the material, the smaller will be the openings in the screen. In such instance, a suitable scraper, or the like, may be attached to apron 143.

It is to be noted that impellers 130 can accommodate considerable fluctuation in feed, and each large compartment tank 126 is always filled to the discharge level 141, so that the speed of impellers 130 need not be as closely controlled as the speed of the drive shafts of the endless conveyor disclosed in the aforesaid co-pending application. Also, since an endless conveyor is not employed in the present application, the cells may be disposed on a single level, either in line or in a circular or other formation, and cells may be added or subtracted as desired. It will further be understood that the cells may be disposed vertically, or in stepped arrangement, one above the other, and that the liquid may be pumped from cell to cell, although a gravity flow from cell to cell is preferred, for economy and simplicity.

From the foregoing, it will be apparent that the method and apparatus of this application attains the objects specified in my aforesaid application and herein, and further that the method and apparatus of this invention permit the treatment of a wide variety of materials. It will also be understood that many other embodiments of the invention exist, and that various changes in the method and apparatus may be made without departing from the spirit and scope of the invention.

What is claimed is:

1. Apparatus for treating divided solids material with a liquid, which comprises a plurality of spaced vertical housings, each housing being substantially rectangular in shape at the top, and circular in shape at the bottom; a plurality of spaced vertical substantially cylindrical tanks, alternating with respect to said housings and connected with said housings so as to form a plurality of connected stages, each stage including an interconnected housing and tank, each tank having a lower end of reduced cross sectional area; an impeller mounted at the connection between the tank and housing; a conduit leading from the outlet of said impeller to the lower end of the tank of the same stage; means for rotating said impeller; agitating and stirring means mounted in said tank; means for rotating said agitating and stirring means; means for supplying divided solids to the upper end of the housing of the first stage; means for supplying fresh liquid to the upper end of the housing of the last stage in series; a horizontally disposed, rotating cylindrical screen device for removing liquid from each tank adjacent the upper end thereof, said screen device being rotated in a direction tending to move divided solids out of said tank; an apron mounted adjacent the rotating screen device of at least each stage except the last for receiving said divided solids and directing the same to the upper end of the housing of the cell next in series; and a plurality of liquid conduits leading from each end of the rotating screen device of each stage except the first to a point intermediate the upper and lower ends of the housing of the next stage.

2. Apparatus for treating divided solids materials with a liquid comprising a pair of elongated substantially vertical chambers in side by side relation, the first of said chambers having openings adjacent its upper end adapted to receive said solids materials and liquid, the second of said chambers having an outlet opening for treated liquid adjacent its upper end at an elevation greater than the elevation of said liquid inlet opening in said first chamber, rotary impeller means disposed adjacent the lower ends of said chambers, structural means defining the inlet and discharge zones of said rotary impeller, said inlet defining structural means being directly connected to the lower end of said first chamber to deliver the intermixed solids and liquid in said first chamber under a hydraulic pressure head to said impeller, and said outlet defining structural means being connected to the lower end of said second chamber for delivering the impeller agitated intermixed solids and liquid under an increased pressure head upwardly through said second chamber for separate discharge.

3. Apparatus for treating divided solids materials with a liquid comprising a pair of elongated substantially vertical chambers in side by side relation, the first of said chambers having

openings adjacent its upper end adapted to receive said solids materials and liquid, the second of said chambers having an outlet opening for treated liquid adjacent its upper end at an elevation greater than the elevation of said liquid inlet opening in said first chamber, rotary impeller means disposed adjacent the lower ends of said chambers, structural means defining the inlet and discharge zones of said rotary impeller, said inlet defining structural means being directly connected to the lower end of said first chamber to deliver the intermixed solids and liquid in said first chamber under a hydraulic pressure head to said impeller, said outlet defining structural means being connected to the lower end of said second chamber for delivering the impeller agitated intermixed solids and liquid under an increased pressure head upwardly through said second chamber for separate discharge, and stirring means in said second chamber

5

for maintaining the intermixed relation of said solids and liquid.
